UNITED STATES PATENT OFFICE.

JOHN P. CLARK, OF LEETONIA, OHIO.

VALVE.

1,179,281.

Specification of Letters Patent. Patented Apr. 11, 1916.

Application filed February 16, 1915. Serial No. 8,652.

To all whom it may concern:

Be it known that I, JOHN P. CLARK, a citizen of the United States, residing at Leetonia, in the county of Columbiana and

5 State of Ohio, have invented new and useful Improvements in Valves, of which the following is a specification.

This invention relates to valves and more particularly to safety gas valves.

10 The principal object of the invention is to provide an improved type of pressure regulated gas valves which act upon a predetermined decrease in the pressure to automatically cut off the supply to the jets. It frequently occurs that during the night when pressure is cut down that low lights will flicker out with the result that the room is subsequently flooded with gas.

15 It is the object of the invention to avoid these difficulties and broadly speaking the invention consists in providing a valve which is held in open position by a predetermined pressure of gas and when released by reduction of the pressure will gravitate to 20 closed position and be locked by suitable mechanism. Means is also provided for preventing the actuation of the locking means when desired.

25 Further objects of the invention will appear as the following description is read in connection with the accompanying drawing, which forms a part of this application, and in which:—

30 Figure 1 is a longitudinal sectional view. Fig. 2 is a vertical section of Fig. 1 showing the valve and the valve seat and the manner in which the former is arranged within the casing. Fig. 3 is a top plan view showing one of the plungers in position to prevent 35 the operation of the locking means. Fig. 4 is a detail perspective view showing a modified form.

35 Referring to the drawings, and more particularly to Figs. 1 and 2, 1 represents a pipe having an apertured diaphragm 2 extending across the same and provided with a valve seat 3 upon which the valve 4 is adapted to rest, as will be hereinafter described. This valve is provided with an annular groove 40 which produces shoulders 6, and slides through the pipe 1 transversely across a casing 7 secured to the top of the pipe in air-tight relation. This casing is provided with suitable packing nuts or glands 8 in which 45 are slidably mounted the locking plungers 9 automatically actuated to engage the groove

6 by means of the springs 10 which surround the plungers 11 between the ends of the casing and suitable collars 12 carried by the plungers. 60

The springs 10 are very light and do not hold the plungers against the valve with sufficient force to hold the valve against normal downward movement when the pressure in the pipe is reduced to a predetermined 65 degree, but are sufficiently strong to move the plungers toward each other for engagement with the annular groove 6 and shoulder 7 when the valve drops to its seat 3. The top of the casing is provided with an 70 aperture 13 through which the valve may be passed to throw it to operative position and this aperture is covered by the cap plate 14 removably connected to the casing by screws or other fastening devices 15. 75

In order to hold the plungers against operation to automatically lock the valve in depressed position when this member is lowered the plungers are provided with laterally extending pins 16 which travel in 80 grooves 17 formed in the packing nuts 8. When the plungers are withdrawn sufficiently to release the pins from the groove and given a slight turn the pins will engage the outer end of the packing nuts and limit 85 the inward movement of the plungers.

In the modification shown in Fig. 4 the valve 4 is provided with an annular groove 18 having the lower wall thereof serrated or roughened, as shown at 19, so as to be engaged by the pawls 20 pivoted upon the ends of the plungers 10. In this form when the valve drops a predetermined degree the pawls move downwardly with the valve and catch upon the serrated shoulder 19, thus 90 holding the valve in depressed position. In this instance, the plungers are normally held in the positions shown but may be retracted against the tension of their springs 10 so as to permit the elevation of the plunger on the pressure of the gas passing through the port or aperture in the diaphragm. 95

100 It will be seen from the foregoing that as the valve is held in open position by the pressure of the gas in the pipe that as soon as a predetermined reduction in the pressure takes place the valve will be gravitationally seated and the plungers will be automatically forced into the groove, thus locking the valve against movement irrespective of 105 any subsequent rise in pressure which may take place. It will, of course, be understood 110

that the pipe 1 is adapted to be connected at one end to a suitable source of gas supply and at the opposite end to the house pipes.

What is claimed is:—

- 5 1. In combination, a gas service pipe having an apertured valve seat member extending across the same, a casing mounted upon the pipe, a valve extending transversely through said casing and slidably mounted therein, an annular groove for said valve and disposed within said casing, plungers slidably mounted within the said casing and having the confronting ends thereof engaging said valve within said groove, and
- 10 15 springs encircling each of said plungers and adapted to actuate said plungers to engage the groove of said valve.
- 15 2. The combination, in a service pipe having an apertured valve seat, extending across the same, a casing mounted upon the pipe, a

valve extending transversely through said casing and working in said valve seat, said valve provided with a groove which is disposed within said casing, plungers slidably mounted within said casing and disposed at 25 the opposite sides of said valve, serrations formed on the lower wall of the said groove, pawls pivotally mounted on the confronting ends of each of said plungers and adapted to be engaged by said serrations when the 30 valve is in closed position, and springs encircling each of said plungers and adapted to actuate said rods to cause the pawls to engage the serrations.

In testimony whereof I affix my signature 35 in presence of two witnesses.

JOHN P. CLARK.
